UNITED STATES PATENT OFFICE.

JOHN F. POLLOCK, OF PIMA, ARIZONA.

DESIGN FOR A STAND FOR DECORATIVE PURPOSES.

Application filed November 5, 1923. Serial No. 7,686. Term of patent 14 years.

To all whom it may concern:

Be it known that I, JOHN F. POLLOCK, a citizen of the United States of America, residing at Pima, in the county of Graham and State of Arizona, have invented a new, original, and ornamental Design for a Stand for Decorative Purposes, of which the following is a specification, reference being had to the accompanying drawings, forming a part hereof.

The figure is a perspective view showing my new, original and ornamental design for a stand for decorative purposes.

I claim:

The ornamental design for a stand for decorative purposes as shown.

JOHN F. POLLOCK.

Witnesses:

A. E. WEECH,
M. A. TAYLOR.
